John Ericson
by his attorney,
Charles R. Scarle.

UNITED STATES PATENT OFFICE.

JOHN ERICSON, OF NEW YORK, N. Y.

MATCH HOLDER AND DISPENSER.

1,281,920.

Specification of Letters Patent. Patented Oct. 15, 1918.

Application filed June 4, 1918. Serial No. 238,076.

To all whom it may concern:

Be it known that I, JOHN ERICSON, a citizen of the United States, residing in the city of New York, borough and county of Bronx, 5 in the State of New York, have invented a certain new and useful Improvement in Match Holders and Dispensers, of which the following is a specification.

The invention relates to holders adapted 10 to contain a supply of matches or analogous articles, and deliver them singly as required, and the object of the invention is to provide a device of this character which shall be simple in construction, offer a single match 15 conveniently presented for removal, and be easily operated to present a succeeding match by the act of removing the first presented.

Another important object is to provide 20 means for agitating the mass of matches in the receptacle to insure proper arrangement of the matches for selection, and means for insuring the progress of the selected matches to the point of delivery in proper position 25 for removal, and a further object is to provide means for permitting the movements of the agitating, selecting, and delivering mechanism without danger of clogging or derangement.

30 The invention consists in certain novel features and details of construction and arrangement by which the above and other objects are attained, to be hereinafter described and claimed.

35 The accompanying drawings form a part of this specification and show the invention as it has been carried out in practice.

Figure 1 is a front elevation of the holder with a match presented for removal.

40 Fig. 2 is a vertical section taken on the line 2-2 in Figs. 1 and 3, and partly in elevation.

Fig. 3 is a vertical section taken at a right angle to Fig. 2, on the line 3-3 in such 45 figure, showing the selecting and delivery mechanism in elevation as seen from the rear.

Fig. 4 is a horizontal section and plan view, the line of section being indicated at 50 4-4 in Fig. 2.

Fig. 5 is a horizontal section taken on the line 5-5 in Fig. 2 and partly in plan view.

Fig. 6 is a vertical section and elevation

corresponding to Fig. 3 but with the slide 55 removed.

Fig. 7 is an elevation of the slide alone.

Fig. 8 is a vertical section of such slide.

Fig. 9 is a vertical section corresponding to Fig. 2 but with certain parts omitted to 60 show the operation of the mechanism.

Fig. 10 is a horizontal section taken on the line 10-10 in Fig. 6 and showing a detail.

Fig. 11 is a vertical section, partly in 65 elevation, showing a modification of the match-ejector.

Similar letters of reference indicate the same parts in all the figures.

The holder is preferably of sheet metal of 70 rectangular form adapted to be supported perpendicularly upon a wall or like surface, and comprises two principal parts, a relatively stationary body or casing and a vertically movable slide or carrier mounted 75 therein. The upper part of the body serves as a receptacle for the supply of matches, and the slide carries a plurality or series of matches delivered thereto from the receptacle and lying in horizontal superposed position, 80 and also presents a match from the bottom of such series in position for removal.

The body consists of two plane sides A, a plane back A¹ extending above the sides and serving as a means for supporting the device, and a front A² having the central portion raised on the rear face as at a for a portion of its height, and provided with a vertical notch a¹ in the lower end of the depressed panel thus formed on the front 90 face. A hinged cover A³ closes the receptacle, and the width of the latter is just enough greater than the length of the matches to be dispensed as to permit the supply to lie freely therein in transverse 95 parallel relation to each other. The wide plane raised portion a on the inner face of the front A² produces a shallow groove at each margin of the front adapted to accommodate the match-heads, as will be described.

At about the mid-height of the body is a deck or platform A⁴ serving as the bottom of the receptacle, and inclined downwardly from the back A¹ toward the front, terminating near the latter in a depending flange A⁵ leaving a narrow passage in which the upper end of a carrier or slide B may move verti-

cally and project into the match receptacle above the floor A⁴.

The slide B is a plate of sheet metal having its margins on each side folded backward upon themselves to form grooves b engaging with vertical ways A⁶ A⁶ on the inner faces of the sides A A, as shown in Fig. 5. The space between the plate B and front A² forms a channel E for the reception of matches from the receptacle.

The lower end of the plate or slide B is notched as at b¹ to correspond with the notch a¹ in the front, and the lower edges of the legs thus formed are bent forward at a right angle to produce ledges B¹ B¹ extending toward the front and adapted to support the ends of a match M extending transversely across the notch, as in Figs. 1 and 3.

20 A wire or shaft C mounted in inwardly extended lugs A⁷ on flange A⁵ serves as a center for the swinging portions of the selecting and liberating mechanism operated by the up and down movements of the slide B. D is a restraining plate hinged on the shaft C and having two separated downwardly extending arms D¹ D¹ each having on its outer edge a toothed spur D² extending through a slot b² in the plate B and into the channel E, adapted to impinge against the lowermost match of the series in the channel and hold it by compression against the front A², as in Fig. 2 and thus support the series. The spurs are held in yielding engagement with the match by a spring C¹ on the shaft, and are swung rearwardly out of such engagement at the proper time by arms F¹ F¹ of a lifting plate F which is mounted to swing on the shaft C immediately in rear of the restraining plate D and carries a transverse bar F², which is shown as continued upwardly and rearwardly on each side, terminating in fingers F³ F³ curved concentrically to the shaft and adapted to enter the match receptacle through holes a² provided in the deck A⁴ and agitate the contained mass of matches. The lifting plate F and its fingers F³ are swung rearwardly by the contact of a yielding cam surface against the bar F² in the downward movement of the slide. The cam surface is shown as a flat spring B² carried on the slide B and curved inwardly and upwardly, and the inward movement of the lifting plate F is communicated to the restraining plate D by the overhanging ends of the lugs D³ D³ on the latter, see Fig. 10, which partially inclose the arms F¹ F¹. The plate F is held in light yielding contact with the cam B² by a spring F⁴ on the shaft C.

Outside the plates D and F, and mounted on the shaft C, are two strips G G each held yieldingly forward by a spring G³ on the shaft C, and each terminates in a

hooked finger G¹ arranged to enter the slot b² at a point below the toothed spur D² and extend across the channel E to support the series of matches when released by the withdrawal of the spurs. The strips G G are swung rearwardly to withdraw the hooked fingers by cams or lugs B³ B³ on the slide B arranged to contact with shoulders G² G² when the slide is elevated.

Contractile springs H H attached at one end to hooks A⁸ A⁸ on the under face of the deck A⁴, and at the other end to pins B⁴ on the slide, tend to keep the slide in the elevated position, with the lugs B⁵ B⁵ at the upper ends of the side-flanges in contact with the stops A⁹ A⁹ on the ways, and the hooked fingers G¹ withdrawn from the channel E; and the downward movement of the slide is limited by the contact of the same lugs B⁵ against the stop-screws A¹⁰ A¹⁰ projecting inwardly from the sides A A.

At each side of the slide B adjacent the notch b¹ and immediately above the ledges B¹ B¹ is an opening b³ receiving a rearward swell J¹ on a spring arm J mounted on the front face of the slide; the inclined rear faces of the swells J¹ J¹ are located to ride upon fixed inclined pins A¹¹ A¹¹ secured to the sides A A of the casing or body, on the downward movement of the slide, and force the spring arms J J forwardly to dislodge and eject a match supported on the ledges B¹ B¹.

A¹² is a narrow downwardly inclined shelf or deflector on the inner face of the front A² above the channel E and its slide B, serving to provide a space free from matches which the upper end of the slide may enter unobstructedly in its upward movement and thus avoid lifting the entire mass and the consequent disarrangement and danger of clogging due to shifting the supply of matches in the receptacle.

B⁶ is a finger-piece on the inner face of the slide at the top of the notch b, by which the slide may be drawn down in initiating the delivery of the matches, by inserting a finger through the notch.

The operation is as follows:—The receptacle is supplied with matches lying transversely therein, parallel with each other and preferably with the heads lying approximately alternately half to the right and half to the left; the slide is drawn down to the limit of its movement by grasping the finger-piece B⁶, thus lowering the top of the slide below the forward edge of the deck A⁴ and permitting matches M to roll by gravity from the deck into the channel in a superposed series of single matches, the lowermost resting on the hooked fingers G¹ G¹. On releasing the slide the springs H H return it to its elevated position, and the fingers G¹ G¹ are withdrawn from the channel by the action of the lugs B³ B³, but just

prior to such withdrawal or before its completion, the toothed spurs $D^2 D^2$ enter the slots $b^2 b^2$ and engage the match next above the lowermost and thus maintain the support of the series while the lowermost match 5 is released and falls upon the ledges $B^1 B^1$ where it is presented for removal extended across the notches a^1 and b^1 but still retained securely in the channel. This upward 10 movement carries the upper end of the slide, into the open space beneath the shelf A^{12} , leaving the remainder of the series in a stationary condition supported by the engagement of the toothed spurs $D^2 D^2$ with the 15 match now serving as the lowermost.

The presented match is removed by grasping it between the finger and thumb and forcing it downward with the slide; this movement brings the inclined faces of the 20 swells $J^1 J^1$ into contact with the fixed arms $A^{11} A^{11}$ and gently forces the match off the ledges to release the slide and permit it to rise again under the influence of the springs $H H$. The downward movement draws the 25 curved flat spring or cam B^2 against the bar F^2 , thus swinging the lifting plate and thrusting the fingers $F^3 F^3$ through the deck A^4 into the mass of matches M , agitating such mass and tending to force a portion toward the front beneath the shelf A^{12} and 30 present them favorably for entrance to the channel E . The swing of the lifting-plate F thus induced brings its arms $F^1 F^1$ into contact with the lugs $D^3 D^3$ on the restraining plate D and compels the latter to swing correspondingly and withdraw the toothed spurs $D^2 D^2$ and permit the series to descend to the hooked fingers $G^1 G^1$ which have been presented below the series by 35 the withdrawal of the lugs $B^3 B^3$ from the shoulders $G^2 G^2$ which movement permits the strips $G G$ again to swing toward the slide B .

At the next upward movement of the 40 slide, the lowermost match of the series is freed and descends while the succeeding match is engaged by the toothed spurs $D^2 D^2$ and the series thus supported, as above described. Each removal of a match frees the 45 succeeding match and conditions it for presentation, and the downward movement permits additional matches from the supply to enter the channel E and maintain a sufficient number in the series.

50 These movements are indicated in Fig. 9 in which the operating means are omitted for clarity.

It will be noted that the action is automatic and practically positive, while the 55 mechanism is yielding in character to avoid danger of fracture or distortion due to obstructions offered by occasional broken or greatly misshapen matches.

By making one side or face of the channel E relatively fixed, as by the front A^2 , 60

and the other movable, as by the slide B , there is a tendency to agitate the series by a rolling motion, thus facilitating the passage of irregular or abnormally thick matches which otherwise would clog the 70 channel.

The shelf A^{12} not only affords a clear space into which the end of the slide may enter with any matches lifted thereby, but also serves to present matches which roll 75 down its upper surface, in position for entering the channel, and also limits or regulates the number of matches in the immediate vicinity of the channel entrance and lessens the tendency to crowd at such entrance.

The raised panel in the center of the front A^2 on its back face provides the extra width or shallow grooves required at each side of the channel to accommodate the heads of the 85 matches.

The stirring fingers $F^3 F^3$ operate in the direction to move the matches in the receptacle toward the channel ready to enter beneath the shelf A^{12} , and by reason of the 90 form of the flat spring B^2 the force required to move such fingers into the mass of matches is greater at the beginning of the movement and gradually decreases, while the force required to stretch the springs H 95 H and depress the slide gradually increases, resulting in a tendency to balance one against the other and make the force required to lower the slide practically constant throughout the lowering movement. 100

The agitating or stirring fingers $F^3 F^3$ move slowly and thus permit the matches in their paths to move relatively to each other and to rearrange themselves without liability to jam. If the fingers strike against a 105 match or group of matches so embedded in the mass as to be practically immovable, the yielding quality of the spring cam B^2 permits the fingers to be thus arrested in their movement and the operation stopped 110 without danger of crushing or breaking such matches or of deranging the mechanism.

Other forms of ejecting mechanism may be substituted for the spring-arms $J J$ and 115 their actuating pins $A^{11} A^{11}$, or the latter may be set farther forward to act directly upon the presented match and force it from the ledges, as shown in Fig. 11 in which the inclined pins A^{13} are received in slots b^4 provided in the slide B^7 and ledges B^8 .

Although the invention is shown and described as applied in dispensing matches, it will be understood that it will serve successfully in dispensing other articles to 125 which it may be adapted.

I claim:

1. In a device of the character set forth, a body having a receptacle for articles to be dispensed, and having a fixed wall form- 130

ing one face of a channel leading from said receptacle, a slide movably mounted in said body and forming the opposite face of such channel, and means actuated by the movements of said slide for delivering such articles through such channel.

2. In a device of the character set forth, a body having a receptacle for articles to be dispensed, and having a fixed wall forming one face of a channel leading from said receptacle, a slide movably mounted in said body and forming the opposite face of such channel, the latter adapted to receive such articles in superposed series, and means actuated by the movements of said slide for separating and presenting the lowermost of such series for removal.

3. In a device of the character set forth, a body having a receptacle for articles to be dispensed, and having a fixed wall forming one face of a channel leading from said receptacle, a slide movably mounted in said body and forming the opposite face of such channel, the latter adapted to receive such articles in superposed series, means actuated by the movements of said slide for separating and presenting the lowermost of such series for removal from such channel, said slide arranged to be operated by the removal of such presented article.

4. In a device of the character set forth, a body having a receptacle therein adapted to contain matches, and having a fixed wall forming one face of a channel leading from said receptacle, a slide movably mounted in said body and forming the opposite face of such channel, the latter adapted to receive matches in superposed series, and means actuated by the movements of said slide for presenting the lowermost of such series for removal from such channel, said slide arranged to be actuated by the removal of such presented match, said fixed wall having a groove at each side to receive the heads of matches in such series.

5. In a device of the character set forth, a body having a receptacle for articles to be dispensed, a channel leading from said receptacle and adapted to receive such articles in superposed series, a slide movably mounted in said body and forming one face of such channel, means actuated by the movements of said slide for delivering such articles through such channel, and an inclined shelf in said body above said slide, arranged to hold back the mass of such articles in said receptacle and provide an unobstructed space into which said slide projects.

6. In a device of the character set forth, a body, a deck therein forming with said body a receptacle for a supply of articles to be dispensed, a slide movably mounted in said body and forming one face of a channel leading from said receptacle, and movable

agitating fingers arranged to project through said deck into such supply and move such articles toward the entrance to such channel.

7. In a device of the character set forth, a body, a deck therein forming with said body a receptacle for a supply of articles to be dispensed, a slide movably mounted in said body and forming one face of a channel leading from said receptacle, movable agitating fingers arranged to project through said deck into such supply and move such articles toward the entrance to such channel, and means actuated by the movements of said slide for moving said agitating fingers.

8. In a device of the character set forth, a body, a deck therein forming with said body a receptacle for a supply of articles to be dispensed, a slide movably mounted in said body and forming one face of a channel leading from said receptacle, springs for raising said slide, movable agitating fingers arranged to project through said deck into such supply in the downward movement of said slide and actuated by the latter, and yielding means causing such projecting movement of said fingers, said yielding means arranged to offer a gradually lessening force in such projecting movement as the tensional resistance of said springs increases during the downward movement of said slide.

9. In a device of the character set forth, a body, a receptacle therein for a supply of matches, and having a fixed wall forming one face of a channel leading from said receptacle, said wall having a raised panel on such face, a slide movably mounted in said body and forming the opposite face of such channel, the latter adapted to receive matches in superposed series, and means actuated by the movements of said slide for separating and presenting the lowermost match of such series for removal from said slide and channel, said panel serving to provide a groove at each side of such channel to receive the heads of matches in such series.

10. In a device of the character set forth, a body, an inclined deck therein forming with said body a receptacle for articles to be dispensed, a slide movably mounted in said body and forming a wall of a channel adapted to receive such articles from said receptacle in superposed series, a shaft mounted in said body below said deck, and oscillating means on said shaft actuated by the movements of said slide, for liberating the lowermost article of such series at each reciprocation of said slide.

11. In a device of the character set forth, a body, an inclined deck therein forming with said body a receptacle for articles to be dispensed, a slide movably mounted in said body and forming a wall of a channel

adapted to receive such articles from said receptacle in superposed series, a shaft mounted in said body below said deck, oscillating means on said shaft actuated by the movements of said slide, for liberating the lowermost article of such series at each reciprocation of said slide, and means actuated by the movements of said slide for ejecting such liberated article.

10 12. In a device of the character set forth, a body, a receptacle therein for articles to be dispensed, means for transferring such articles from said receptacle and presenting them singly for removal, means for agitating such articles in said receptacle, said transferring and agitating means actuated simultaneously by the removal of such presented article.

15 13. In a device of the character set forth, a body, a receptacle therein for articles to be dispensed, a channel formed below said receptacle and having one side fixed, and a movable slide forming the opposite side, said channel arranged to receive articles one upon another in series from said receptacle.

20 14. In a device of the character set forth, a body, a receptacle therein for articles to be dispensed, a fixed wall forming one face of a channel, a slide movably mounted and forming the opposite face of such channel, the latter arranged to receive articles one upon another from said receptacle, enlargements in such channel adapted to receive enlarged portions of such articles, and means for presenting such articles singly for removal.

25 15. In a device of the character set forth, a body, a receptacle therein for articles to be dispensed, a fixed wall forming one face of a channel, said wall having a raised panel on such face, a slide movably mounted and forming the opposite face of such channel, the latter arranged to receive articles one upon another in series from said receptacle, and means actuated by said slide for presenting the lowermost article of said series for removal, said panel serving to provide a groove at each side of such channel to receive enlarged portions of such articles in said series.

30 16. In a device of the character set forth, a body, a receptacle therein for articles to be dispensed, a fixed wall forming one face of a channel, a slide movably mounted and forming the opposite face of said channel, the latter arranged to receive articles in superposed series from said receptacle, means located above such channel and slide and serving to induce the presentation of such articles to such channel in a horizontal position, said means also serving to prevent congestion at the entrance to such channel and providing an unobstructed space into which said slide projects.

35 17. In a device of the character set forth,

a body, a receptacle therein for articles to be dispensed, a fixed wall forming one face of a channel, a slide movably mounted and forming the opposite face of such channel, the latter arranged to receive articles one upon another in series from said receptacle, means arranged to enter such channel and engage or release an article of such series, said means mounted on a fixed portion of said body, and means for retaining such released article for removal.

40 18. In a device of the character set forth, a body, a receptacle therein for articles to be dispensed, a fixed wall forming one face of a channel, a slide movably mounted and forming the opposite face of such channel, the latter arranged to receive articles in superposed series from said receptacle, and an inclined shelf inclosing the entrance to such channel and providing an opening at the side thereof and leading thereto when said slide is lowered.

45 19. In a device of the character set forth, a body, a receptacle for articles to be dispensed, a fixed wall forming one face of a channel, a spring-actuated slide forming the opposite face of such channel, the latter arranged to receive articles in superposed series from said receptacle, ledges carried by said slide, means for agitating such articles in said receptacle, means for selecting and presenting articles singly from said series, said agitating, selecting, and presenting means operated simultaneously in one direction by the act of removing such presented single article from said ledges, and in the opposite direction by the action of said spring-actuated slide.

50 20. In a device of the character set forth, a body, a receptacle therein for articles to be dispensed, a fixed wall forming one face of a channel, a movable slide forming the opposite face of such channel, the latter arranged to receive articles in superposed series from said receptacle, agitating means arranged to operate through openings in the bottom of said receptacle and agitate articles therein, and yielding means operating said agitating means and actuated by the movement of said slide.

55 21. In a device of the character set forth, a body, a receptacle therein for articles to be dispensed, a channel arranged to receive articles one upon another in series from said receptacle, curved agitators pivotally mounted and arranged to operate through openings in the bottom of said receptacle to agitate articles therein in the direction toward such channel, means for actuating said agitators, and means for presenting articles singly from such series for removal.

60 22. In a device of the character set forth, a body, a receptacle therein for articles to be dispensed, a spring-tensioned slide forming one face of a channel leading from said re-

- ceptacle, fingers arranged to agitate articles in said receptacle, and yielding means on said slide for actuating said fingers by the movement of said slide, said yielding means arranged to decrease in resistance while the tension of said springs increases with the outward movement of said slide.
23. In a device of the character set forth, a body, a receptacle therein for articles to be dispensed, a fixed wall forming one face of a channel, a slide movably mounted and forming the opposite face of such channel, the latter arranged to receive articles in superposed series from said receptacle, means for presenting articles singly from said series, ledges on said slide supporting such presented article, and means for ejecting such presented article from said ledges.
24. In a device of the character set forth, a body, a receptacle therein for articles to be dispensed, a slide movably mounted in
- 5 10 15 20 25
- said body and forming one face of a channel, such channel arranged to receive such articles in superposed series from said receptacle, and means for agitating such articles in said receptacle, said means actuated by the movement of said slide.
25. In a device of the character set forth, a body, a receptacle therein for articles to be dispensed, a fixed wall forming one face of a channel, a slide movably mounted and forming the opposite face of such channel, the latter arranged to receive such articles one upon another in series from said receptacle, means arranged to enter such channel and engage or release an article of such series, said means mounted on a fixed portion in said body and actuated by the movement of said slide.

In testimony that I claim the invention above set forth I affix my signature.

JOHN ERICSON.
